BARREL BAND SWIVEL

Phil Judd, Butte, Mont.

Application May 20, 1949, Serial No. 94,409

5 Claims. (Cl. 42—85)

The present invention relates to improvements in a barrel band swivel and has for an object to provide an improved swivel for the sling of a rifle or the like which may be quickly and easily attached to and detached from the barrel or fore end portion of the stock.

Another object of the present invention is to provide an improved device of this kind by means of which a sling may be mounted upon a firearm which has not been equipped with a sling at the factory.

A further object of the present invention is to provide an improved barrel band swivel which does not require the services of a gunsmith or other experienced workman to install but may be properly and securely attached by an unskilled person without the use of tools except a screwdriver or a coin.

A still further object of the present invention is to provide an improved structure of this character which may be selectively attached to gun barrels having external diameters of various sizes.

The present invention aims to provide an improved barrel band swivel which for the purpose of attaching or detaching may be slipped over the end of the gun barrel so that it is not necessary to remove any of the permanent fixtures of the gun, such as the magazine tube holder or the front sight.

The present invention also aims to provide an improved device of this type which comprises relatively few parts and requires a relatively small amount of material to make so that the manufacturing costs could be kept low.

In one of its broadest aspects the present invention contemplates the provision of an improved barrel band swivel comprising an interrupted band for embracing a gun barrel, a fastening element mounted on the band for bearing against the barrel to clamp the band tightly on the barrel, a swivel member mounted on the fastening element and a strap holder bow supported by the swivel member for swivel movement thereon.

With the foregoing and other objects in view, the invention will be hereinafter more fully described and more particularly pointed out in the appended claims.

In the drawings, in which the same parts are denoted by the same reference numerals throughout the several views:

Figure 1 is a side elevational view of a gun with an improved barrel band swivel constructed in accordance with the present invention applied thereto;

Figure 2 is an enlarged side elevational view of the improved device shown as applied to a gun barrel a portion of which is illustrated;

Figure 3 is a vertical sectional view taken on the line 3—3 of Figure 2 and looking in the direction of the arrows; and

Figure 4 is a horizontal sectional view taken on the line 4—4 of Figure 3.

Referring more particularly to the drawings, 10 indicates a stock and 11 a barrel of a conventional gun. A gun sling or strap 12 has its rear end portion attached to the stock 10 by an appropriate fastening device 13. The forward end of the strap 12 is adapted to be detachably attached to the gun barrel 11 by an improved barrel band swivel indicated generally at A.

The barrel band swivel comprises an interrupted band 14 of substantially U-shape, the arms 15 and 16 of which are of arcuate formation to conform to the contour of the outer surface of the barrel 11 which they are adapted to embrace. The free end portions of the arms 15 and 16 approach one another but terminate short of each

other to provide a space 17 therebetween to accommodate a front gun sight 18 and its base which are of conventional type so that the band 14 may be slipped along the barrel 11 without removing the gun sight and its base. The band 14 may be approximately three fourths of an inch wide, three-fourths of a complete annulus or circle and the space 17 between the free ends of the arms 15 and 16 may be about seven-sixteenths of an inch.

The band 14 has a screw-threaded opening 19 disposed at a point which is diametrically opposite to the center of the space 17. A fastening element, such as a screw or the like, generally indicated at 20 has a threaded shank 21 which is received by the opening 19 in the band, a pair of spaced-apart annular shoulders 22 and 22a and a neck 23 connecting the shoulders 22 and 22a. The neck 23 is of smaller diameter than that of the shoulders of the screw so that an annular groove 24 is provided between the shoulders 22 and 22a. The screw 20 has an enlarged head 25 the outer surface of which may be rugose and a kerf 26 is formed in the head 25 for the reception of a screwdriver or a coin for rotating the screw.

A swivel member or nut 27 of substantially truncated cone formation has a centrally disposed longitudinally extending through bore 28 therein for the reception of the shank, shoulders and neck of the screw 20. The swivel member 27 is also provided with transverse aligned passageways 29, the inner ends of which communicate with the bore 28 and the annular groove 24. The lower end of the swivel member is engaged by the upper surface of the head 25 of the screw to retain the swivel member on the screw.

A strap ring bow or link 30 has its opposed free end portions 31 extending through the passageways 29 of the swivel member 27 and into the bore 28 of the swivel member and the annular groove 24 of the screw 20. The forward end portion of the strap 12 is detachably looped as at 32 and this looped portion of the strap receives the link 30.

In the use of the device, the band 14, the screw 20, the swivel member 27 and the link 30 are received by the user as an assembled unit so that it is only necessary for the user to slip the band 14 over the forward end of the barrel 11.

The arms 15 and 16 of the band will slide along the barrel and the space 17 between the arms will permit the band to be moved rearwardly without interference on the part of the front gun sight 18 and its base. When the band has been moved to the desired point on the barrel, the screw 20 may be rotated by a coin which may be inserted in the kerf 26 of the head 25 until the flat inner end of the screw 20 is forced against the gun barrel 11 and bears back against the band 14 so that the arms 15 and 16 of the band are drawn into tight frictional engagement with the gun barrel to positively lock the band to the barrel.

The swivel member 27 may freely rotate around the shank of the screw and the ends 31 of the link 30 will be lightly clamped into the annular groove 24 of the screw 20. This arrangement will accomplish the following purposes:

(a) Permits rotation of the sling strap 12 and the loop or link 30 through which the strap 12 is strung.
(b) Prevents the device from coming apart through the normal tension of the sling carry.
(c) Keeps the link 30 from falling or being forced out of the groove 24 and the passageway 29 of the swivel member 27.

(d) Prevents the screw 20 from becoming detached and lost.

(e) Reduces to a minimum the end play of the screw 20.

In order to detach the device, the screw 20 may be rotated in the opposite direction until the inner end thereof disengages the barrel 11 and the band may then be slid off the forward end of the barrel.

By increasing the length of the screw 20, the device may be attached through the wooden fore end 33 of the stock 10 as well as to the naked barrel forwardly of the stock.

It is obvious that various changes and modifications may be made in the details of construction and design

of the above specifically described embodiment of this invention without departing from the spirit thereof, such changes and modifications being restricted only by the scope of the following claims.

What I claim is:

1. A barrel band swivel comprising, a substantially circular band adapted to adjustably embrace a gun barrel, said band having a broken-away portion, said band being provided with a threaded opening oppositely disposed from the central point of said broken-away portion of said band, a set screw provided with a head having a kerf, said set screw having a shank, said shank having an enlarged portion adjacent the head of said set screw, said enlarged portion of said shank being provided with an annular recess, said shank having a reduced threaded free end portion engaging the threaded opening in said band, a rotatable swivel member provided with a longitudinal opening therethrough to receive the enlarged portion of said shank, said rotatable member being provided with two oppositely disposed aligned openings at right angles to the annular recess in the enlarged portion of said shank and communicating therewith, and a strap holder bow provided with two free end portions each engaging through one of said right angle openings in said rotatable member to terminate in the annular recess in the enlarged portion of the shank of said set screw to swingably support said strap holder bow from said rotatable member.

2. A barrel band swivel comprising, a band adapted to adjustably embrace a gun barrel, said band having a broken-away portion, said band being provided with a threaded opening oppositely disposed from said broken-away portion of said band, a set screw provided with a head, said set screw having a shank, said shank having an enlarged portion adjacent the head of said set screw, said enlarged portion of said shank being provided with an annular recess, said shank having a reduced threaded free end portion engaging the threaded opening in said band, a rotatable swivel member provided with a longitudinal opening therethrough to receive the enlarged portion of said shank, said rotatable member being provided with two oppositely disposed aligned openings at right angles to the annular recess in the enlarged portion of said shank and communicating therewith, and a strap holder bow provided with two free end portions each engaging through one of said right angle openings in said rotatable member to terminate in the annular recess in the enlarged portion of the shank of said set screw to swingably support said strap holder bow from said rotatable member.

3. A barrel band swivel comprising, an interrupted band for adjustably embracing a gun barrel, said band being provided with a threaded opening oppositely disposed from the interrupted portion of said band, a fastening element having a threaded portion engaging said threaded opening of the band for initially bearing against the gun barrel in the direction of said interrupted portion of the band to clamp the band tightly on the barrel in the operation of the fastening element, a swivel member mounted on the fastening element, and a strap holder bow supported by the swivel member for swivel movement thereon.
4. A barrel band swivel comprising, a substantially circular interrupted band for adjustably embracing a gun barrel, said band being provided with a threaded opening oppositely disposed from the central point of the interrupted portion of said band, a fastening element having a threaded portion engaging said threaded opening of the band for initially bearing against the gun barrel in the direction of said interrupted portion of the band to clamp the band tightly on the barrel in the operation of the fastening element, a swivel member mounted on the fastening element, and a strap holder bow supported by the swivel member for swivel movement thereon.
5. A removable and adjustable barrel band swivel comprising, an interrupted band for embracing a gun barrel and having a pair of arms, a set screw mounted directly and threaded on the band opposite to the interrupted portion of the band for bearing against the barrel during its first stage of tightening to initially move the barrel against the arms of the band and during its final stage of tightening to subsequently force the arms of the band into tight frictional engagement with the barrel, a swivel member mounted directly on the fastening element, and a strap holder bow supported by the swivel member for swivel movement thereon.
